UNITED STATES PATENT OFFICE

DOROTHY M. NOLAN, OF LOS ANGELES, CALIFORNIA

DESIGN FOR A NOVELTY TOY

Application filed April 13, 1932. Serial No. 43,486. Term of patent 3½ years.

To all whom it may concern:

Be it known that I, DOROTHY M. NOLAN, a citizen of the United States, residing at Los Angeles, in the county of Los Angeles and State of California, have invented a new, original, and ornamental Design for a Novelty Toy, of which the following is a specification, reference being had to the accompanying drawing, forming part thereof, in which the figure is a three-quarters side elevation of a novelty toy, showing my new design.

I claim:

The ornamental design for a novelty toy, substantially as shown.

DOROTHY M. NOLAN.
